UNITED STATES PATENT OFFICE

104,595

DESIGN FOR A COMBINED LANTERN AND BATTERY CASE OR SIMILAR ARTICLE

Eugene W. Weston, Elginburgh, Ontario, Canada

Application April 1, 1936, Serial No. 61,897

Term of patent 14 years

To all whom it may concern:

Be it known that I, Eugene W. Weston, a citizen of the Dominion of Canada, residing at Elginburgh, in the county of Frontenac and the Province of Ontario, Dominion of Canada, have invented a new, original, and ornamental Design for a Combined Lantern and Battery Case or Similar Article, of which the following is a specification, reference being had to the accompanying drawing, forming part thereof.

Figure 1 is a front elevation of a combined lantern and battery case, or similar article, showing my new design.

I claim:

The ornamental design for a combined lantern and battery case or similar article, as shown.

EUGENE W. WESTON.
